UNITED STATES PATENT OFFICE.

FRANK L. WILLIAMS, OF DENVER, COLORADO.

DENTAL INSTRUMENT.

Application filed August 9, 1922. Serial No. 580,717.

To all whom it may concern:

Be it known that I, FRANK L. WILLIAMS, a citizen of the United States, residing at Denver, in the county of Denver and State of Colorado, have invented certain new and useful Improvements in Dental Instruments, of which the following is a specification.

My invention relates to dental instruments of the type shown and described in my applications for patent, Serial Numbers 458,674 and 458,675, filed April 5, 1921, and its primary object is to provide certain improvements in the construction and arrangement of the co-operating parts of an instrument of the above described character which simplify its production, facilitate its operation and enhance the accuracy of the placements produced by relative adjustment of its measuring devices.

With this object in view, my invention resides in the details of construction and arrangement of parts illustrated in the accompanying drawings in which like characters of reference designate corresponding parts throughout the several views and in which—

Figure 1 is a side elevation of the improved instrument;

Figure 2, a plan view of one of the model-holding members looking in the direction of the arrows 2, Figure 1;

Figure 3, an enlarged fragmentary view of the upper portion of the vertically adjustable standard of the supporting element of the instrument showing the application thereto of an upper model-holding member for co-operation with the relatively stationary lower one;

Figure 4, a still further enlarged section on the line 4—4, Figure 3;

Figure 5, a fragmentary end view looking in the direction of the arrow 5 in Figure 1;

Figure 6, a section taken along the line 6—6, Figure 1 and drawn to an enlarged scale;

Figure 7, an enlarged section on the line 7—7, Figure 2;

Figure 8, a fragmentary elevation of the pointer of the measuring device of the instrument looking in the direction of the arrow 8, Figure 1, and drawn to an enlarged scale;

Figure 9, an enlarged plan view of the joint between the instrument proper and the clamp by which it is mounted on a table

or work bench, looking in the direction of the arrow 9, Figure 1;

Figure 10, an enlarged section taken on the line 10—10, Figure 1, looking upwardly;

Figure 11, an enlarged section along the line 11—11, Figure 8; and

Figure 12, a section taken on the line 12—12, Figure 6.

Referring in detail to the drawings, the reference character 13 designates a standard which through the medium of a three-way joint 14 is mounted on a clamp 15 by means of which the instrument is attached at the edge of a table or work bench.

The joint permits of adjustment of the standard so as to place the parts of the instrument and the dental models supported thereon, conveniently within easy reach of the operator.

The standard has a longitudinal slide way, 75 best shown in Figure 12, in which a rack bar 16 is slidably fitted.

A pinion 17 on a shaft 18 which is supported in bearings 19 at the rear side of the standard, meshes with the rack to provide 80 for its up and downward adjustment through manipulation of a knurled head 20 at an end of its shaft.

A nut 21 on the screw threaded opposite end of the shaft, serves to clamp the bar in 85 its adjusted positions.

The standard and the rack bar conjointly constitute the element which serves to hold the members used for the support of dental models, relative to a common occlusal plane, 90 and the measuring devices which in the practice of prosthesis, are employed to indicate the sizes, positions and angles of artificial teeth on one of the models.

With this object in view, the rack bar is 95 provided with means to interchangeably attach the upper model holding member and the measuring element of the instrument, while the relatively stationary standard carries the lower model-clamp as will herein- 100 after be described in detail.

Each model clamp comprises a plate 22 provided with aligned slots 23 for the adjustable support of a pair of co-operating jaws which in practice engage with a dental 105 model placed on the plate and secure it against relative displacement. Each jaw consists of a headed stud 24 which is rotatably supported on a slide block 25 in the respective slot, as best shown in Figure 7 of 110

the drawings, and which carries at its upper end a removably fastened, downwardly curving claw 26.

A nut 27 on the threaded end of the stem, 5 beneath the plate, and a spring washer 28 co-operate to yieldingly secure the stud relative to a model with which its claw engages.

The plate is furthermore provided with a plurality of headed leveling screws 29 which 10 carry cup-shaped contact pieces 30 for engagement with the lower surface of a dental model secured on the plate by means of the co-operating clamps.

It will be seen that the clamps are adapted 15 to bear down on the model to hold it to the plate while the screws permit of final adjustment of the model to accurately place the artificial teeth thereof in an occlusal plane determined by means of the measuring 20 devices of the instrument.

In addition to the above described fastening and adjusting devices, the plates of the model clamps have adjustable means for holding wax trial plates on the models, by 25 engagement with the upper surfaces thereof.

In the construction shown in the drawings, these means consist of a pair of posts 31 which are slidably mounted in parallel slots 32 of the plate and which are fastened 30 in a selected position by means of nuts 33 on their threaded protruding ends.

Pivoted laterally projecting arms 34 at the upper ends of the posts are restricted in 35 their upward movement by springs 35, and fingers 36 pivotally attached at the free ends of the arms, curve downwardly to engage with the trial plate on a model secured to the holding-member.

Each plate is adjustably mounted on a 40 longitudinally slotted base 37 by means of a threaded stud 38 which extends centrally from a central boss 39 on the underside of the plate.

The boss rests against the surface of the 45 base, and the stud projecting through the slot of the same, is provided with a nut 40 and a spring washer 41 to clamp the plate in its adjusted positions.

In order to accurately determine the position 50 of the plate on the base, the latter has a graduated scale 42 which co-operates with an index mark 43 on the boss of the plate, as shown in Figure 1. The base of each model plate, which preferably is made in the form 55 of a bar, has at one end an apertured knuckle 44 for its hinged connection with the bifurcated projection 45 of an arm 46 by which it is connected to the respective member of the holding element of the instrument.

The hinge-connection is made through the 60 medium of a headed pintle 47 in alined apertures of the parts of the knuckle joint, one of said apertures being tapped to co-operate 65 with a screw thread on the pintle, as shown in Figure 5, to fasten the bar in the posi-

tions to which it is adjusted through the instrumentality of a headed screw 48 which projects through a threaded aperture in the free end of the bar to engage with the corresponding end portion of the respective 70 arm. Set-nuts 49 on the screw hold it against accidental rotation.

The arm 46 of the lower model clamp is formed integrally at the lower end of the stationary standard 13 and that of the 75 upper one is removably attached to an overhanging bracket 50 at the upper end of the rack bar.

The arm 46^a has to this end a transversely disposed segmental plate 51 which engages 80 with a similarly formed upright plate 52 at the end of the bracket, and a longitudinally projecting pin 53 which fits into a correspondingly sized bore of the bracket.

A set screw 54 passing through a concentric arcuate slot 55 of the segmental plate of the arm into a screw-threaded aperture of the plate 52 fastens the one plate upon the other, the slot having at one end an enlargement 56 which permits of the plate being 90 set in place without the removal of the set screw from the other plate.

A scale 57 at a beveled edge of the bracket-plate co-operates with an index mark 58 on the corresponding edge of the other plate to 95 accurately determine the position of the upper model-holder relative to the adjustable member of the holding element on which it is mounted.

A fastening identical to that hereinbefore 100 described, is employed to attach the measuring devices of the instrument at the end of the bracket.

A segmental plate 59 is in this case formed 105 at the end of an arm 60 which at its opposite end carries the co-operating parts of the measuring devices. The latter with the exception of one particular, are in form and relative arrangement similar to the corresponding element of the construction disclosed in the last above mentioned applications for patent, and need be but briefly described to convey a complete understanding 110 of the present invention.

A horizontal circular plate 61 fastened 115 at the end of the arm 60 has on its beveled peripheral edge, a graduated scale to indicate the relative positions of a subjacently extending rotary indicator 67.

The latter is mounted to swing about a 120 horizontal axis on a headed pivot pin 64 which is rotatably fitted in a central aperture of the stationary plate, a nut 62 on a projecting screw-threaded end of the pin having been provided to clamp it in its 125 adjusted position.

An index 63 on the head of the pin co-operates with the scale of the plate to designate the relative positions of the parts according to geometric calculations.

A segmental plate 65 fastened on the head of the pivot pin extends alongside of the indicator in a plane parallel to its longitudinal axis and it bears at its peripheral edge, a graduated scale which in the operation of the instrument functions to indicate the angular position of the indicator relative to the vertical passing through its axis of rotation on the plate, by co-operation 10 with an index 66 fastened to a part of the indicator.

It is in the construction of the indicator that the present invention differs somewhat from the constructions shown and described 15 in the prior applications.

The improved indicator which is shown in detail in Figures 8 and 11 of the drawings, consists of a tubular holder 68 which at its upper end is pivotally connected with 20 the head of the pivot pin 64, and a pointer 69 which is slidably fitted in the holder and protrudes through an opening at the lower end thereof. A set screw 70 in a threaded aperture of the holder engages with the 25 pointer to clamp it in its adjusted positions, and an index 71 on the pointer projects through a longitudinal slot 72 of the holder to co-operate with a graduated scale 73 formed alongside of the slot.

30 In order to determine the relative positions of the two members of the supporting element of the instrument, the rack bar carries a pointer 74 which projects through a recess in the face of the relatively stationary standard to co-operate with a graduated scale 75 at a side of the slot.

This scale which in the operation of the instrument, is fixed in the standard, is relatively adjustable to enable the up and down- 40 ward measurements to be calculated from a zero point the position of which varies according to that of the occlusal plane of a dental model on the lower clamp-member.

The scale is to this end formed in a plate 45 76 which is slidably fitted in the recess of the standard and which has a longitudinal slot for the protrusion of the index on the rack bar.

A set screw 77 in a threaded aperture of 50 the standard at a side of its recess has a head engaging with the face of the scale to secure it in its adjusted positions, and a scale 78 on the face of the standard at an edge of its recess, is provided to indicate 55 the positions of the slide.

Having thus described the improvements in the construction and arrangement of the parts of the instrument, their advantages will be readily understood and appreciated 60 by those versed in the art to which the invention appertains.

In the operation of the instrument, the occlusal plane of a dental model on the lower clamping member is determined by a 65 swinging movement of the indicator about

its vertical axis; the width, angle and relative position of artificial teeth on the model are established through the medium of the different scales of the measuring device by reference to geometric charts which designate the graduations on the scales with which the respective indexes must register to place the teeth in the proper position in the occlusal plane, and the position of the teeth in an upper model relative to those on the lower one is established by replacing the arm carrying the measuring device, on the bracket of the rack bar, by the one to which the upper clamping member is secured.

What I claim and desire to secure by Letters Patent is:

1. An instrument of the character described comprising a standard, means for fixing it in a projecting position on a support, an extension vertically adjustably mounted on the standard, means to effect said adjustment, a model support fixed at the lower portion of the standard in a projecting position, and a measuring instrument co-operative with said model support 85 extending from the upper end of the extension.

2. An instrument of the character described comprising an upright composed of two members one of which is vertically slideable relative to the other, a model support extending from said other member, a second model support, and a measuring device each adapted for co-operation with the first mentioned support in a superposed position, 95 the second model support and the measuring device being adapted to be interchangeably attached at the upper end of the adjustable member of the upright, and means to effect 100 said attachment.

3. An instrument of the character described comprising an upright composed of two members one of which is vertically slideable relative to the other, a model support extending from said other member, an element co-operative with said model support in a superposed position and adapted for attachment at the upper end of the adjustable member, and means to effect said attachment, said element and said adjustable member bearing registering marks whereby one can be placed in a predetermined position relative to the other.

4. An instrument of the character described comprising an upright composed of two members one of which is vertically adjustable relative to the other, a model support on said other member, an element at the upper end of the adjustable member adapted for co-operation with said support in a superposed position, a vertically adjustable scale on one of the members and an index cooperating therewith on the other.

5. An instrument of the character described comprising an upright composed of 130

4

5 a supporting member and a member which is vertically adjustable within the other, a model support on the supporting member, an element at the upper end of the adjustable member adapted for co-operation with the model support in a superposed relation thereto, a slotted plate slideable on the supporting member and bearing a graduated scale, means for securing said plate in its 10 adjusted positions, and an index on the adjustable member, extending through the slot of the plate and co-operating with the scale.

6. An instrument of the character described comprising an upright composed of 15 a supporting member and a member which is vertically adjustable relative to the other, a model support on the supporting member, an element at the upper end of the adjustable member adapted for co-operation with 20 said support in a superposed relation thereto, two co-operating scales on the supporting member one of which is vertically adjustable with relation to the other, and an index on the adjustable member co-operating with 25 the adjustable scale.

7. An instrument of the character described comprising a model support, and a measuring device co-operative with the model support in superposed relation thereto and including an indicatory element composed of a tubular longitudinally slotted holder bearing a graduated scale, a pointer slideable in the holder and carrying an index projecting through the slot thereof and co-operating with the scale, and means to lock the pointer in its adjusted positions.

8. An instrument of the character described comprising a model support and a measuring device superposed thereon and 40 including a pointer, the support having a base member pivoted for angular adjustment, means for holding the member in adjusted positions, a model carrying plate slideable on the member to locate the model 45 with relation to the pointer, and means for locking the plate in adjusted positions.

9. An instrument of the character described comprising a model support and a measuring device superposed thereon and 50 including a pointer, the support having a model carrying plate slideable to locate the model with relation to the pointer, a scale to predetermine the location of the plate, and means for fastening the plate in adjusted 55 positions.

10. An instrument of the character described comprising an upright a model support thereon, an element superposed above said model support, a means for fastening 60 the upright, and a connection between the upright and said means including pivotal joints to permit of the movement of the up-

right about a vertical axis and a relatively transverse axis.

11. In an instrument of the character described, a support, an arm projecting therefrom in a substantially horizontal position, a base member pivoted on the arm on a horizontal axis for upward and downward adjustment, model fastening means on the member, and an adjusting screw loosely supporting the base member in its adjusted positions upon the arm. 65 70

12. In an instrument of the character described, a measuring instrument including 75 a pointer having a circular movement about a fixed axis, a model-support including a model holding member and connections between said model support and said model holding member whereby the latter may be adjusted to place a dental model fastened thereon in a plane at a predetermined angle to said axis. 80

13. In an instrument of the character described, a measuring instrument including 85 a longitudinally extensible pointer having a circular movement about a fixed axis, a model support including a model-holding member and connections between said model support and said model holding member whereby the latter may be adjusted to place a dental model fastened thereon in a plane 90 at a predetermined angle to said axis. 95

14. In an instrument of the character described, the combination with a support for 100 a dental model, of a thereto superposed instrument including a pointer and connections between said instrument and said pointer whereby the latter may be adjusted to different points in the occlusal arch of a dental model on the support, and scale-means co-operative with the pointer to designate the position of the pointer in the occlusal arch according to predetermined 105 measurements.

15. In an instrument of the character described, the combination with a holding element, of a support for a dental model, an instrument removably fastened on the holding element and including a pointer and connections between said instrument and said pointer whereby the latter may be adjusted to different points in the occlusal arch of a dental model on the support, and scale-means co-operative with the pointer to designate the position of the pointer in the occlusal arch according to predetermined 110 measurements, and a second dental-model-support adapted to replace the instrument in its superposed relation to the first mentioned support. 115

In testimony whereof I have affixed my signature.

FRANK L. WILLIAMS.
